CHUCK FOR CAMSHAFTS AND THE LIKE

William F. Groene, Cincinnati, Ohio, assignor to
 The R. K. Le Blond Machine Tool Company,
 Cincinnati, Ohio, a corporation of Ohio

Application October 28, 1936, Serial No. 108,039

12 Claims.

(Cl. 82—1)

This invention pertains to a method and chuck for supporting and rotating camshafts whereby turning operations may be simultaneously undertaken on all the journal bearings. Heretofore, two or more different machining operations were necessary to completely turn these journal bearings. This multitude of operations was required because the nature of a camshaft is such that a large number of cutting tools cannot be applied thereto without considerable distortion and twisting of the work piece, unless it can be positively held and rotated in such a manner to permit the application of cutting tools to all the journal bearings simultaneously. Prior to my invention no method or means had been devised to support and rotate a camshaft so as to meet these requirements.

This invention is particularly adapted to machines of the character shown in application Serial No. 121,510 filed January 21, 1937.

An object of my invention is the provision of a novel method of preparing and chucking an unfinished camshaft intermediate its ends whereby it may be positively centered and rotated.

Another object is the preparation of a portion of an unfinished camshaft whereby it may be accurately chucked intermediate its ends so as to expose all of the journal bearings for simultaneous turning.

Another object is to provide on an unfinished camshaft a finished cylindrical surface and a driving lug associated therewith whereby said camshaft may be accurately centered and positively driven intermediate its ends.

Further objects will appear in the course of the following description of the drawings in which:—

Figure I is an end view of a center drive chuck, utilizing the principles of my invention, showing a camshaft held in working position.

Figure II is a section on line II—II of Figure I particularly showing the centering and driving members engaging a camshaft and the clamping cam for actuating the clamping jaws.

Figure III illustrates a typical camshaft for an internal combustion engine showing particularly the finished cylindrical portion and driving lug.

Figure IV is a transverse section on line IV—IV of Figure III showing the driving lug adjacent a cam lobe.

Figure V is an axial view of the clamping cam.

Figure VI is a side view of the clamping cam to clearly show the tapered cam portions.

Figure VII is an end view, partly in section on

line VII—VII of Figure II, showing the clamping cam rotated to force the arcuate clamping jaws into contact with the work piece.

Briefly in the practice of my invention, I provide a chucking device having a fixed member adapted to receive and support a finished cylindrical portion of a work piece for centering said work piece; a fixed member adapted to engage a driving lug on the work piece for rotating said work piece; and suitable clamping means to hold the cylindrical portion in engagement with said supporting member.

In the practice of my invention I also provide in a chuck clamping means comprising a pair of arcuate jaws and cam means for actuating said jaws, the cam means being rotatable for moving the jaws to and from a work piece in the chuck and movable axially for adjusting the cam means so as to move the jaws in predetermined relation to said work piece.

In Figure III is illustrated a typical internal combustion engine camshaft comprising the main shaft portion 1, the journal bearings 2, 3, 4, and 5, the cam lobes 6, an eccentric 7 for fuel pump actuation, concentric portions 8, for steady rest purposes in machining the shaft, and the distributor drive gear portion 9. In order to prepare the camshaft in carrying out my invention I propose to premachine a concentric cylindrical portion on the shaft as for example the portion 9 and also to provide a driving lug 10 formed integral with the shaft at the time of forging or casting the camshaft. In the particular example of Figure III, I have shown the lug 10 formed adjacent one of the cam lobes 6. The purpose of this is to give added rigidity and strength to the lug which it must have to withstand the cutting strains imposed on it when tools are simultaneously operating on the journal bearings 2, 3, 4, and 5. The lug 10 is also arranged on the camshaft in close proximity to the machined portion 9.

The combination of the machined portion 9 and the lug 10 constitutes one position of engagement for chucking and driving the camshaft. It is also fully within the scope of my invention to provide a plurality of such positions for chucking. For example the portions 8 might be premachined and appropriate lugs provided adjacent these portions so that the camshaft 50 might be chucked and driven at a plurality of points along the shaft, a very desirable arrangement when working upon extremely long camshafts with large numbers of journal bearings to be machined. Also, by utilizing chucking de-

vices at two or more points on the camshaft said shafts may be centered and axially aligned in the machine without the use of any centering means in the ends of the shaft, this feature being particularly valuable when it is desirable simultaneously to machine the ends 11 and 12 of the shaft.

I have illustrated in Figures I and II one form of chucking device adapted to utilize the cam-shaft prepared for turning the journal bearings as described above. The chuck is of the center drive type comprising a ring gear 13 journaled on suitable anti-friction bearings 14 and 15 carried in the frame 16 of a lathe. The ring gear 15 has suitable gear teeth 17 formed around its periphery which are engaged by a suitable driving pinion 18 for rotation of the ring gear 13 as is usual for center drive chucks.

The bearing 14 is retained on the ring gear 13 by suitable retaining plate 19 held to the ring gear by screws 20. The bearing 15 is retained on the ring gear 13 by the retaining plate 21 held to the ring gear 13 by screws 22.

The ring gear 13 has a straight bore 23 and a connecting tapered bore 24; the plate 21 likewise has a straight bore 25 and a connecting tapered bore 26. In a suitable recess 27 in the ring gear and the plate 21, is fixed the centering and locating member 28 to the surface 29 of the ring gear 13 by means of suitable screws 30. The member 28 has an arcuate bearing portion 31 facing toward the axis of the chuck and adapted to receive and center the portion 9 of the cam-shaft.

35 The driving member 32 is secured to the member 28 by suitable screws 33 and has a slot 34 facing toward the axis of the chuck. The slot engages the lug 10 of the camshaft so as to cause the camshaft positively to be rotated upon rotation of the ring gear 13.

Suitable clamping means is provided for holding the portion 9 in contact with the bearing receiving portion 31 of the member 28. Such means preferably comprise arcuate clamps 35 and 36 slidable in suitable arcuate guideways 37 and 38 formed in the ring gear 13, the jaws being held in said guideways by the plate 21.

Resilient means are preferably provided for normally urging the jaws away from contact 50 with the work piece. A convenient arrangement comprises engaging gear teeth 41 cut on the periphery of the jaws 35 and 36. The plungers 39 are urged upwardly (Fig. I) by means of the springs 42, the plungers and springs being carried in suitable guideways 43 formed in the ring gear 13 and confined therein by the plate 21. The work engaging ends 44 and 45 of the jaws 35 and 36 are formed as concave surfaces nicely fitting the periphery of the portion 9 of the cam-shaft.

The means for controlling the movement of the jaws 35 and 36 to and from the work piece is the rotatable clamping cam 46. This cam has a bearing portion 47 journaled in the bushing 48 and a bearing portion 49 journaled in the bushing 50 fixed in the ring gear 13. The bushing 48 is mounted in the threaded bore 51 in the plate 21 and is provided with splines 52 at its outer end whereby it may be rotated by a suitable spanner wrench for axial adjustment in the bore, 51. A locking means for holding the bushing 48 in adjusted position comprises the ring 53 having a splined bore 54 fitting over the splines 52 of the bushing 48 and secured to the plate 21 by screws 55.

The clamping cam element 46 has a flanged portion 56 adjacent the bearing portion 47 which abuts against the inner face of the bushing 48 to limit the axial movement of the cam 46 away from the clamping jaws 35 and 36. Intermediate 5 of the flanged portion 56 and the bearing portion 49 is the tapered actuating cam portion 57 having convex cam surfaces 58, on the opposite end limits thereof. These cam surfaces 58 are angularly related to the axis of rotation of the clamping cam member 46 and engage angularly related surfaces 59 formed on the outer ends of the clamping jaws 35 and 36, as seen in Figs. I, II, and VII, when the cam member 46 is rotated to unclamped position, Figures V and VII, the surfaces 60 of the outer ends of the jaws 35 and 36 bear against the faces 61 of the portion 57 to arrest further outward movement of the jaws 35 and 36 under the influence of the springs 42. A suitable socket 62 for a wrench provides means 20 for manually rotating the clamping cam 46.

It can be clearly seen that the tapered construction of the surfaces 58 and 59 will cause the clamping cam 46 to be urged axially away from the clamping jaws 35 and 36 so as to cause the face 56 to abut against the bushing 48, and also that by proper axial adjustment of the bushing 46 the surfaces 58 and 59 may be so relatively adjusted as to give the proper camming action for the clamping cam 46 and the proper engagement of the work engaging portions 44 and 45 on the portion 9 of the work piece.

Having fully described my invention, what I claim and desire to secure by Letters Patent is:

1. A process of treating unmachined camshafts having a main shaft portion, journal bearings, and cam lobes for simultaneously finishing a plurality of said journal bearings in a single chucking operation, which comprises forming a driving lug on said shaft and machining a cylindrical portion on said shaft concentric with its axis of rotation, and chucking said work in a chucking device, said work piece being centered by engagement of said cylindrical portion with a work locating abutment on said chuck fixed with respect to the center of rotation of said chuck and the clamping of said portion thereagainst, said work piece being rotated by said chucking device by engagement of said driving lug with a driving abutment fixed on said chuck.

2. A process of treating unmachined camshafts having a main shaft portion, journal bearings, and cam lobes for simultaneously finishing a plurality of said journal bearings in a single chucking operation, which comprises forming axially spaced driving lugs on said shaft and machining axially spaced cylindrical portions on said shaft concentric with its axis of rotation, chucking said work in a plurality of chucking devices, simultaneously finishing a plurality of said journal bearings, in said chucking operation, said work piece being centered solely by engagement of said cylindrical portions with work locating abutments on said chucks fixed with respect to the center of rotation of said chuck and the clamping of said portions thereagainst, said work piece being rotated by said chucking devices by engagement of said driving lugs with driving abutments fixed on said chucks.

3. The method of chucking a camshaft for machining the journal bearings thereof, which comprising finishing a cylindrical area on the shaft concentric with its axis of rotation and forming a projecting driving lug on said shaft adjacent said area, and supporting the shaft so

prepared in a suitable chucking device by definitely located abutment means of the device presenting abutment areas to said cylindrical area and said lug, said cylindrical area serving to center said shaft, and said lug serving to drive said shaft.

4. The method of chucking a camshaft for machining all the journal bearings thereof simultaneously, which comprises finishing a cylindrical area on the shaft concentric with its axis of rotation and forming a driving lug on said shaft adjacent said area, and supporting the shaft so prepared in a center drive chucking device by definitely located abutment means of the device presenting abutment areas to said cylindrical area and said lug, said cylindrical area serving to center said shaft, and said lug serving to rotate said shaft upon rotation of said chucking device.

5. In a center drive chuck, means presenting surfaces equidistant from the chuck axis at one side thereof to receive a cylindrical part of a work piece and hold it coaxial with the chuck, said chuck having arcuate guides at opposite sides of said means, arcuate jaws guided in said guides, each adapted to present an end to an area of the cylindrical part of the work, which areas are spaced apart along a line beyond the axis of the chuck from said first mentioned surfaces, a clamping cam acting against the opposite ends of both of said jaws to force them against said work, said clamping cam comprising a rotatable element having peripheral cam portions diametrically opposite each other, each of said portions being adapted to engage an end of a jaw, and means on said chuck to engage another part of the work to cause the work piece to rotate with the chuck.

6. A center drive chuck as set forth in claim 5 wherein the cam portions are angularly disposed relative to each other and to the axis of rotation of said rotatable element.

7. In a center drive chuck having an axial bore, work surface engaging centering means located in said bore, arcuately guided clamping means to engage the surface beyond the center from the centering means, and means to straddle another part of the work adjacent said centering means, said straddling means being adapted positively to drive a work piece in the chuck.

8. In a center drive chuck, means for accurately centering and positively driving a work piece, arcuate guides at opposite sides of said means, arcuate jaws guided in said guides each present-

ing an end to a part of the work piece, a clamping cam comprising a rotatable element, having peripheral cam portions formed thereon substantially diametrically opposite each other, acting against the opposite ends of both jaws to force them against the work piece, and resilient means acting to withdraw said jaws from the work as the jaws are relieved of the action of said clamping cam.

9. In a center drive chuck, means for accurately centering and positively driving a work piece, arcuate guides at opposite sides of said means, arcuate jaws guided in said guides, each to present an end to a part of the work piece, a clamping cam comprising a rotatable element, having peripheral cam portions formed thereon substantially diametrically opposite each other and angularly related to the axis of rotation of said rotatable element, said cam portions acting against the opposite ends of both jaws to force them against the work piece, and means for axially adjusting said rotatable element relative to said jaws.

10. In a chucking device for camshaft, means to engage the premachined periphery of the distributor drive gear portion of the camshaft so as to center the shaft in the chuck, abutment means to engage a driving abutment means on the shaft so as positively to rotate the shaft with the chuck, and clamping means engaging said distributor drive gear portion to hold said shaft engaged with said centering means.

11. In a chucking device for camshaft, means to engage premachined cylindrical areas on the main shaft portion of the camshaft so as to center the shaft in the chuck, abutment means to engage driving abutment means on the shaft so as to positively rotate the shaft with the chuck, and clamping means engaging said cylindrical areas to hold said shaft engaged with said centering means, said driving abutment means constituting a projecting integral driving lug formed on the shaft adjacent to said premachined cylindrical areas.

12. In a center drive chuck, means to engage axially spaced premachined cylindrical areas on a work piece so as to center and axially align the work piece in the chuck, abutment means to engage driving abutment means on said work piece so as to positively rotate the work piece with the chuck, and clamping means engaging said cylindrical areas to hold said work piece engaged with said centering means.

WILLIAM F. GROENE.
